The ornamental design for a cap, as shown and described.

DESCRIPTION

FIG. 1 is a top front right perspective view of a cap showing our new design;
 FIG. 2 is a top view thereof;
 FIG. 3 is a right side view thereof;
 FIG. 4 is a left side view thereof;
 FIG. 5 is a front view thereof;
 FIG. 6 is a rear view thereof;
 FIG. 7 is a top front right perspective view of FIGS. 1-6 in an in-use, open position;
 FIG. 8 is a top view thereof;
 FIG. 9 is a right side view thereof;
 FIG. 10 is a left side view thereof;
 FIG. 11 is a front view thereof; and,
 FIG. 12 is a rear view thereof.

The uneven-length broken lines represent unclaimed boundaries of the claimed design. The even-length broken lines showing the remainder of the CAP are for environmental purposes only and form no part of the claimed design.
